(74) **Attorney, Agent, or Firm:** — McAndrews, Held & Malloy, Ltd.

(57) **CLAIM**

The ornamental design for a case for mobile electronic device, as shown and described.

DESCRIPTION

FIG. 1 is a top front perspective view of a case for mobile electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a bottom rear perspective view thereof.

(Continued)

The dashed broken lines in the figures depict portions of the case for mobile electronic device that form no part of the claimed design.

1 Claim, 6 Drawing Sheets
